(57) **CLAIM**

The ornamental design for a wearable ECG patch, as shown and described.

DESCRIPTION

FIG. 1 is a perspective view of a wearable ECG patch, showing our new design.

FIG. 2 is a right-side view thereof.

FIG. 3 is a left-side view thereof.

FIG. 4 is a top view thereof.

FIG. 5 is a bottom view thereof.

FIG. 6 is a front view thereof.

FIG. 7 is a rear view thereof; and,

FIG. 8 is a perspective view of a lower portion thereof, when separated from the remainder of the wearable ECG patch. The broken lines in the drawings depict portions of the wearable ECG patch that form no part of the claimed design.
